DESIGN FOR A COMBINATION KEY AND KNIFE

Walter H. Voos, Mount Carmel, Conn.

Application August 8, 1939, Serial No. 86,539

Term of patent 14 years

To all whom it may concern:

Be it known that I, Walter H. Voos, a citizen of the United States of America, residing at Mount Carmel, county of New Haven, State of Connecticut, have invented a new, original, and ornamental Design for a Combination Key and Knife, of which the following is a specification, reference being had to the accompanying drawing, forming a part thereof.

Fig. 1 is an exploded side elevational view of a knife casing and a key;

Fig. 2 is an elevation with the key inserted in the key casing; and

Fig. 3 is an edge view of the disclosure shown in Fig. 2 showing my new design.

The dominant feature of the design is the combination of a knife casing and key as illustrated in Figs. 2 and 3.

I claim:

The ornamental design for a combination key and knife, substantially as shown and described.

WALTER H. VOOS.
